UNITED STATES PATENT OFFICE.

WILLIAM A. KNOWLES, OF ALAMEDA, CALIFORNIA.

DENTAL ENGINE.

SPECIFICATION forming part of Letters Patent No. 372,317, dated November 1, 1887.

Application filed May 14, 1887. Serial No. 238,166. (No model.)

To all whom it may concern:

Be it known that I, WILLIAM A. KNOWLES, a citizen of the United States, residing in the city and county of Alameda and State of California, have invented a new and useful Dental Engine, of which the following is a specification.

My invention relates to improvements in dental engines, which will be understood by reference to the accompanying drawings and the letters referring thereto.

Figure 1 is a side elevation showing the crane-arm in section and broken off and a broken part of the cable-sleeve; Fig. 2, a side elevation showing the cable-sleeve and cable-rod broken off; Fig. 3, a longitudinal sectional elevation of the same, as shown in Fig. 1; and Fig. 4 is a side elevation of a machine constructed in the simplest form, without any means of tipping the cable down when not in use. Fig. 5 is an enlarged broken view of the tip-down bracket M, designed to show the stop-spring S more clearly than it is shown in Figs. 1 and 2.

A represents the end of any crane lever or arm to which my improvement is attached; B, the top frame for the reversing-gear and driving-pulley; C, the set-screw for the top of the driving-spindle; D, the lock-lever for the set-screw C, to prevent the same from loosening; E, the lock-spring, which operates the lock-lever D to hold it in place; F, the spindle for the driving-pulley and reversing-gear; G, the upper, and H the lower, bevel-wheel of the reversing-gear; I, the driving-pulley; J, the driving-cord; K, the bevel-pinion which drives the cable; L, the supporting-bracket sleeve shown in Fig. 4, and M the pivoted bracket shown in Figs. 1, 2, and 3; N, the pivot, by means of which the bracket M is hinged; O, the lock-lever for holding the bracket M in gear; P, the thumb-piece for operating the lever O in unlocking the same.

Q represents the cam-sleeve for shifting the pinion K in and out of gear with the bevel-gear G and H to reverse the drill-cable; R, the adjusting-slot in the sleeve Q, for adjusting or shifting bevel-pinion K; S, the spring cam-stop for holding the pinion K in gear with either the wheel G or H.

T represents the cam-sleeve knob or thumb-piece; U, the attaching-post for the cable.

driving pinion; V, the head-block for the cable-sleeve; W, the cable-sleeve.

X represents the adjusting-collar; Y, the set-screw for setting the adjusting-collar fast.

Z represents the stop-rest by which the machine is held in gear.

A' represents the vertical guide-slot in the bracket M, to allow the post U to be raised and lowered and the gear to be reversed.

B' represents the adjusting-pin which is attached to the post U, and operates through the vertical guide-slot A' and the cam guide-slot R.

C' represents the cable-rod.

D' represents the spring which returns the lock-lever O.

E' represents the hanging pivot post, which forms the bearing for the supporting-bracket sleeve L and the step or bearing for the spindle F to revolve in.

G' represents a stop.

The following is the operation of my improved engine: In Fig. 1 the pinion K is shown in gear with the bevel-wheel H, and the driving-cord J revolves the pulley I continuously in the same direction. The thumb-piece T is now thrown out to the left and held in that position by the cam or inclined spring-cam S, while the pin B', being held at one position laterally, is forced down by means of the angular slot R, thus keeping the pinion K in gear with the bevel-wheel H and revolving the same in a corresponding direction. To reverse the action of the pinion K, the thumb-piece T is operated, turning the cam-sleeve Q and moving the slot R over the pin B', thereby raising the pinion K up against the wheel G and causing it to revolve in the opposite direction.

As the thumb-piece T is passed over the spring cam-stop S, the stop S rises up behind the same, thus holding it in place and the pinion K in gear, as has been shown. It will be seen that as the supporting-sleeve L has its bearing upon the hanging-post E' and revolves concentrically with the spindle F, it may be revolved about four-fifths of a revolution, thereby allowing the drill-cable to be used in any required direction horizontally.

The object of employing the collar X is to allow the removal and the adjustment of the supporting-bracket sleeve L and to take up any unnecessary vertical movement in the fit-

ting upon the hanging-post E'. When it is required to tip the cable down, (as is customary for preserving the flexible cable,) the lock-lever O is tipped down by pressing the thumb-piece P, and the stop-rest Z is released and the cable is turned down, the bracket turning upon the pivot N. When raised again, it is only necessary to raise the cable-sleeve W to a horizontal position, when the stop rest Z passes to the end of the lock-lever O, and the spring D' throws the lock-lever O in behind the same, thereby locking the pinion K in gear with either the bevel-wheel G or H, as it may be set.

15 The set-screw C is furnished with a concave bearing for the top of the spindle F, and when turned to the right point for the required bearing the catch-lever D is dropped between the cogs, and holds the same from turning back. 20 The lever D is held in contact by the spring E, as shown in Figs. 1 and 3.

Having thus described my invention, what I claim, and desire to secure by Letters Patent, is, in dental engines—

25 1. The combination, with a crane or supporting-arm A, of the top frame, B, the cone-bearing C, the lock-lever D, the spring E, and the hanging pivot-post E', for the purpose of supporting and adjusting the spindle F, and gear G, H, and I, constructed and operated substantially as and for the purposes set forth.

30 2. The combination, with a crane or supporting-arm, A, of the top frame, B, the cone-bearing C, the lock-lever D, the spring E, the

hanging pivot-post E', and the adjusting collar X and set-screw Y, for the purpose of supporting and adjusting the spindle F, the gear G, H, and I, and furnishing a bearing and adjustment for the supporting sleeve-bracket L, constructed and operated substantially as and for the purposes set forth. 40

3. The combination, with a crane or supporting-arm A, having a top frame, B, of a cone-bearing C, the lock-lever D, spring E, 45 the hanging pivot-post E', the adjusting collar X, the supporting-bracket sleeve L, with lever O and P, and spring D', for the purpose of adjusting and operating the tip-down bracket M, constructed and operated substantially as and for the purposes set forth. 50

4. The bracket M, hinged at N, having the spring cam or stop S, the vertical slot A, and the lock-notch Z and stop G', in combination with the cam-sleeve Q, having the angular slot R, and thumb piece T, and with the attaching pivot-post U, having the adjusting-pin B', and with the supporting-bracket sleeve L, having the lock-lever O, with thumb-piece P, and spring D', for the purpose of releasing the 60 tip-down bracket M, allowing the cable-sleeve W to swing horizontally, and for reversing the movement of the drill-cable, constructed and operated substantially as and for the purposes set forth. 55

WILLIAM A. KNOWLES.
